Primary Examiner — T. Chase Nelson*Assistant Examiner* — Jonathan J Han*(74) Attorney, Agent, or Firm* — Sutherland Asbill & Brennan LLP(57) **CLAIM**

The ornamental design for a trigger, as shown and described.

DESCRIPTION

FIG. 1 is a perspective view of a trigger for a firearm according to an embodiment of the disclosure;

FIG. 2 is a another perspective view thereof;

FIG. 3 is a front view thereof;

FIG. 4 is a back view thereof;

FIG. 5 is a side view thereof;

FIG. 6 is a another side view thereof;

FIG. 7 is a top view thereof;

FIG. 8 is a bottom view thereof; and,

FIG. 9 is a side view thereof.

The broken line circular elements in FIGS. 1, 2, 5, 6, and 9 depict portions of the trigger that form no part of the claimed design. The broken line depiction of a firearm in FIG. 9 is for the purpose of illustrating environmental structure associated with the design in a condition of use, and also forms no part of the claimed design.

1 Claim, 4 Drawing Sheets(56)
